UNITED STATES PATENT OFFICE.

EUGENE C. JOHNSON, OF LOS ANGELES, CALIFORNIA.

RAIL-CONTACTOR.

1,238,922.

Specification of Letters Patent. Patented Sept. 4, 1917.

Application filed August 12, 1916. Serial No. 114,560.

To all whom it may concern:

Be it known that I, EUGENE C. JOHNSON, a citizen of the United States, residing at Los Angeles, in the county of Los Angeles and State of California, have invented a new and useful Rail-Contactor, of which the following is a specification.

This invention relates to devices of the character designed to close an electric circuit automatically by the passing of rolling stock over the rail of a railroad and an object of the invention is to make provision for reliable operation of the device so that it will not fail to work.

15 Devices of this character are often used in connection with an electric circuit for operating a signal and it is obvious that such devices should be so constructed that they will be proof against failure to operate.

20 Another object of this invention is to utilize the downward pressure or movement of the rail for closing the electric circuit.

Another object of the invention is to provide a device of this character of maximum 25 simplicity in order to minimize the liability of its getting out of order and failing to function properly.

Another object is to so construct the device that the interior parts thereof will be readily 30 accessible for inspection and replacement of parts if such inspection or replacement becomes advisable or necessary.

Other objects and advantages will appear in the subjoined detail description.

35 The accompanying drawings illustrate the invention:

Figure 1 is a plan view of a device embodying the invention, portions of the rail and tie being broken away to contract the 40 view.

Fig. 2 is an enlarged cross section on line indicated by x^2-x^2 , Fig. 1.

Fig. 3 is a vertical section on line indicated by x^3-x^3 , Fig. 2, the rail and the tie 45 being omitted.

Fig. 4 is a plan view of the device shown in the preceding figures, the cover being omitted for clearness of illustration.

Fig. 5 is a diagram of connections which 50 may be employed.

One of the rails of a railroad track is indicated fragmentarily at 1 and one of the ties for supporting said rail is indicated fragmentarily at 2. The present device embodying the invention is located between the tie 2 and the flange 3 of the rail and is of

such construction that the weight of rolling stock running on the rail 1 causes downward pressure of the rail to operate the device to close the electric circuit of which, if 60 desired, the rail may be an element.

There is provided a box or case comprising an upper member or cover 4 and a lower member or base 5 in telescopic relation with one another. The cover 4 is constructed of 65 electrical conductive material and is in direct electrical contact with the bottom face of the rail flange 3; and the base 5 rests on the upper face of the tie 2 and is firmly fixed thereto, the base 5 for this purpose being 70 provided with laterally extending flanges 6 having perforations 7 through which are inserted spikes 8 engaging the tie 2.

The cover 4 has a downwardly projecting flange 9 extending around the four sides of the cover, and the base 5 has an upwardly projecting flange 10 fitting closely inside of the flange 9 around the four sides of the base so as to exclude dirt and water from the interior of the box. Inside of the box base 5 80 is an upper electrical contact plate or member 11 which is insulated from the base by an insulation member 12 of any suitable insulating material. Resting on the base 5 are upwardly projecting longitudinally extending insulation strips 13 and transversely extending insulation strips 14, together forming an upwardly projecting insulating flange surrounding the insulation member 12 and the plate 11 and projecting 85 above said plate to form a recess 15 into which extends a downwardly projecting boss forming an upper electrical contact plate 16 of the cover 4, the sides of said boss closely fitting against and in sliding contact 90 with the inside faces of the insulation strips 13, 14, that thus act as insulated guides for the boss. The upper face of the plate 11 and the lower face of the plate 16 are normally held spaced apart from one another by suitable means to form an air gap a therebetween; and said means in the instance shown 95 comprise springs or spring disks 17 mounted in the four corners of the box on fillers 18 between said fillers and the cover 4 in the space b surrounding the boss 16.

The space between the flange 10 and the top of the cover 4 and between the insulation strips 13, 14 and said top is always slightly greater than the gap a or space between the contact plates 11, 16 so that when 110 rolling stock is on the rail and causes the

contact plates to engage one another all of the load will come on said contact plates and be supported thereby. If all of the load of the rolling stock is supported by the means relied upon to yieldingly hold the contacts separated, it is obvious that said yielding means will rapidly deteriorate in resiliency so that the air gap between the contacts will become less and less until, in time, said gap is no longer sufficient to keep the circuit open.

The springs 17 may be of any desired strength, for instance, of a strength sufficient to maintain the contacts 19, 20 spaced from one another when the weight of the rolling stock is less than a predetermined maximum and of a strength insufficient to maintain said contacts spaced from one another when said predetermined weight is equaled or exceeded. Thus it is clear that the springs 17 can be of sufficient strength to admit of a hand car or inspector's car passing over the rail without the weight of said car operating to close the electric circuit, and of insufficient strength to admit of a passenger or freight train passing without the weight of said train causing closing of the circuit and actuation of any current-energizable device that may be in said circuit. If the electric current to be employed in connection with the device were relatively strong, the adjacent faces of the contact plates 11 and 16 could alone be relied upon for forming an electrical contact when said faces are moved into engagement with one another, but to insure that the device operate perfectly when the electric current is relatively weak there is provided on the under face of the plate 16 a supplemental contact 19 of platinum or equivalent adapted to engage, when the cover 4 is depressed for that purpose, a contact 20 at one end of a resilient member in the form of a leaf spring 21 which is accommodated in a recess 22 formed in the upper face of the contact plate 11, said leaf spring being firmly fixed on the plate 11 by rivets or equivalents 23.

As indicated in Fig. 5 the plate 11 is connected by a conductor 24 to a current-energizable device 25 in the form of a lamp or relay or any device that it is desirable to energize by electric current when the cover 4 is depressed. The current-energizable device is connected by a conductor 26 to any suitable source of power; indicated in this instance as a battery 27, and said battery in turn is connected by a conductor 28 to the rail 1 which, as has been previously stated, is in electrical contact with the cover 4.

From the foregoing it is clear that in practical operation, rolling stock, not shown, when passing over the portion of the rail 35 adjacent the tie 2, if said rolling stock be

not less than the weight determined by the resistance of the springs 17, will depress or deflect said portion of the rail against the pressure of the springs 17 to bring about engagement of the contacts 19, 20 to close the electric circuit and thereby energize the current-energizable device 25.

It is thus seen that the weight of rolling stock passing over the rail is instrumental in causing the closing of the electric circuit. 75

It is obvious that the conductor 28 may be connected directly to the upper contact plate 16 instead of to the rail if desired.

I claim:

1. The combination with a rail, of a lower contact plate, an upper contact plate above the lower contact plate and operative by movement of the rail, and means tending to hold the contact plates apart, said means allowing the contact plates to engage one another and to support the load when rolling stock is on the rail.

2. In combination, a box comprising a cover and base in telescopic relation with one another, a rail partly resting on the cover, means yieldingly holding the cover in raised position against the pressure of the rail thereon, and means operative by movement of said cover to close an electric circuit. 95

3. In combination, a box having two members provided with flanges interfitting one another, means in the box tending to force said members away from one another, and means operative by relative movement of the members toward one another to close an electric circuit. 100

4. In combination, a base, a contact plate insulated from said base, insulation strips surrounding the contact plate and projecting above the upper surface thereof to form a recess, said strips being spaced from the cover, a cover having a second contact plate projecting into the recess and fitting against the inside faces of said insulation strips, and means tending to force the cover and base away from one another. 110

5. In combination, a base, a contact plate insulated from said base, a cover having a second contact plate, means tending to raise the cover away from the base, there being a recess in one of the contact plates, a leaf spring in the recess of said contact plate, a contact on the other one of said contact plates, and a contact on the leaf spring to engage the contact on the contact plate when the cover is depressed. 115

6. In combination, a base, a contact plate insulated from said base, insulation strips surrounding the contact plate and projecting above the upper surface thereof to form a recess, a cover having a second contact plate projecting into the recess and fitting against the inside faces of said insulation strips, means tending to force the cover 125

and base away from one another, there being a recess in one of the contact plates, a leaf spring in the recess of said contact plate, a contact on the other one of said contact plates, and a contact on the leaf spring to engage the contact on the contact plate when the cover is depressed.

7. In combination, a rail, an upper contact plate operative by movement of said rail, a lower contact plate below said upper contact plate, and supplementary contacts for the contact plates adapted when the rail is depressed to engage one another before the contact plates engage one another.

8. The combination with a rail, of a lower 15 electric contact plate, and an upper electric contact plate above and normally spaced from the lower contact plate and operative by movement of the rail to engage the lower contact plate, said lower contact plate alone 20 supporting the load when rolling stock is on the rail.

Signed at Los Angeles, California, this 3d day of August, 1916.
